Patented June 11, 1918.

FIG. 4

Julius R. Watts
Inventor
By *Geo. H. Kimmel*

Attorney

UNITED STATES PATENT OFFICE.

JULIUS R. WATTS, OF ATLANTA, GEORGIA.

BOOK-MARK.

1,269,025.

Specification of Letters Patent. Patented June 11, 1918.

Application filed September 19, 1917. Serial No. 192,122.

To all whom it may concern:

Be it known that I, JULIUS R. WATTS, a citizen of the United States, residing at Atlanta, in the county of Fulton and State of Georgia, have invented certain new and useful Improvements in Book-Marks, of which the following is a specification.

This invention relates to book marks and it is the dominant object of the invention to 10 provide a book mark which can be detachably secured to a book without mutilating the same and placed between the pages thereof marking the same.

It is a more specific object of the invention 15 to provide a novel clip adapted for engagement with a book back and having a marker secured thereto for arrangement between the book pages.

The improvements in the details and arrangement of parts will be apparent from 20 an inspection of the accompanying drawings, in connection with the specific description hereinafter contained, and wherein the preferred embodiment of the invention is 25 disclosed for the purpose of imparting a full understanding of the same.

In the drawings:—

Figure 1 is a side elevation of the mark as applied to a book back;

30 Fig. 2 is a vertical fragmentary section through a book showing the mark applied thereto;

Fig. 3 is a horizontal section through the book back showing the arrangement of the 35 clip; and

Fig. 4 is an elevation of the improved mark.

Having more particular reference to the drawings, and in connection with which like 40 reference character will refer to corresponding parts throughout the several views, B represents a book back to which the improved mark is applied.

The mark includes a clip formed from a 45 single piece of spring metal and bent upon itself, one leg portion thereof being widened and formed concavo-convex as indicated by the reference numeral 1 and having a plurality of tits formed upon the under side thereof, as shown at 2, these tits, obviously serv-

ing as means for gripping the book back and preventing undue displacement of the clip. The remaining leg portion of the clip designated by the numeral 3 is somewhat longer than the first mentioned portion and 55 when engaged with a book is arranged upon the inner side of the back thereof. The intermediate portion of the clip is curved or enlarged as at 4 and provided with a key hole slot 5 in which one end of a ribbon or 60 flexible marker 6 is inserted, as shown in the Fig. 2. It is of course to be understood, that that end of the flexible marker as engaged in the slot 5 is knotted.

When in using the improved book mark, 65 the spring metal clip is engaged with the back thereof as shown in the drawings and the flexible mark 6 arranged between the desired pages. It will be readily understood, that the construction of the clip is such as 70 to prevent the mutilating or scarring of the book back and yet, add to the ornamental appearance thereof.

The exposed portion of the clip may be provided with an ornamental design while 75 the clip itself may be, if desired, formed of precious or attractive metal.

It is of course to be understood that the clip may be formed of various materials instead of metal, such as card-board, fiber, 80 hard rubber, etc.

Manifestly, the construction shown is capable of considerable modification and such modification as is within the scope of my claims, I consider within the spirit of my 85 invention.

I claim:—

A book marker including a clip formed of a single piece of spring metal bent upon itself and adapted to be detachably engaged 90 with a book back, the intermediate portion of said clip being enlarged and provided with a slot, one side of the clip being widened and formed concavo-convex, a plurality of tits formed on said concavo-convex side, and 95 a flexible marker engaged with said slot.

In testimony whereof, I affix my signature hereto.

JULIUS R. WATTS.
